UNITED STATES PATENT OFFICE.

ZENA WATTS, OF CHICAGO, ILLINOIS.

TONGS.

Application filed October 2, 1920. Serial No. 414,163.

To all whom it may concern:

Be it known that I, ZENA WATTS, a citizen of the United States, residing at Chicago, in the county of Cook and State of Illinois, have invented new and useful Improvements in Tongs, of which the following is a specification.

This invention relates to tongs, and an object of the invention is to provide a set 10 of tongs which can easily be manipulated by one hand of the user, a weighted hand grip being provided to facilitate the opening or spreading of the jaws of the tongs.

A further object of this invention is to 15 provide a pair of tongs of the nature specified, which are particularly adapted for household use, such as removing clothes from a boiler of boiling water.

Further objects of the invention will appear in the following description and accompanying drawings in which:

Fig. 1 is a side elevation of the improved tongs showing the jaws open.

Fig. 2 is a side elevation of the improved 25 tongs showing the jaws closed.

Referring more particularly to the drawings, the improved tongs 1 comprise the jaw levers 2 and 3 which are pivotally connected intermediate their ends by a rivet 4. The portions of the jaw lever 2 and 3 outwardly of the pivot 4 thereof are curved to provide gripping jaws as indicated at 5 and 6 respectively for gripping any object desired. The end portions of the levers 35 remote from the jaws 5 and 6 are slightly increased in width and are bent at acute angles to the enlarged portions of the jaws, providing angled connecting portions 7 and 8 to the terminals of which links 9 and 10 respectively are pivotally connected. The links 9 and 10 are also pivotally connected, as shown at 11, to the handle 12. The handle 12 comprises the hand grip 13, which is formed partly by the opening 14 in the handle 12, as clearly shown in the drawing, the handle 12 is weighted at its lower portion as at 15 to facilitate the opening of the jaws 5 and 6. In use, when the tongs are lifted or raised, or in other words, when 40 pressure is exerted outwardly from the pivot 4 of the levers 2 and 3, the jaws 5 and 6 are brought together as indicated in Fig. 2 of the drawing for securely gripping any desired article, however when such outward pressure is relieved, the weight of the

weighted portion 15 of the handle 12 will cause the handle to move toward the pivot 4 and spread the jaws 5 and 6, thereby eliminating the necessity of using both hands either for opening or closing the jaws of the 60 tongs.

From the drawing it will be noted that all the pivots in the tongs extend in the same direction, and transversely to the direction of spreading of the jaws, thereby 65 permitting the jaws to be either opened or closed by movement of the handle 12 towards or from the pivot 4.

From the foregoing description taken in connection with the accompanying drawing 70 it will be apparent that a pair of tongs has been provided which can be economically constructed and one which is durable and efficient in operation, permitting a firm gripping action of the jaws 5 and 6 with 75 minimum effort of the user as well as one in which minimum effort and exertion will be required to open the jaws.

It is, of course, to be understood that the invention may be constructed in various 80 other ways and the parts associated in different relations and, therefore, I do not desire to be limited in any manner except as set forth in the claims hereunto appended.

Having thus described my invention what I claim is:

1. Tongs comprising a pair of jaws pivoted together and a weighted hand grip having flexible connection with the jaws. 85

2. Tongs comprising a pair of jaws pivotally connected, a hand grip consisting of a handle and a weight depending therefrom and links connecting the weight to the jaws. 90

3. In a pair of tongs, jaw levers pivoted intermediate their ends, jaws thereon, links pivotally connected to the jaw levers at their ends remote from the jaws, a handle pivoted to said links, the pivots of the links and handle extending parallel with the pivots of the jaw levers whereby the jaws will be opened or closed upon movement of the handle towards or from the pivot of the jaw levers, said handle having its portion adjacent to the pivot of the jaw levers 100 weighted to facilitate the opening of the jaws. 105

In testimony whereof I affix my signature.

ZENA WATTS.
